UNITED STATES PATENT OFFICE.

JAMES H. RAND, JR., OF TONAWANDA, NEW YORK.

CARD-INDEX DEVICE.

Application filed October 15, 1923. Serial No. 668,632.

To all whom it may concern:

Be it known that I, JAMES H. RAND, Jr., a citizen of the United States, residing at Tonawanda, in the county of Erie and State 5 of New York, have invented a new and useful Improvement in Card-Index Devices, of which the following is a specification.

This invention relates to card indices and more particularly to that type of index in 10 which a plurality of members or cards are maintained in overlapping arrangement in a tray or drawer with the edges of the cards projecting one beyond the other.

In indices of this kind members have been 15 provided having means for attachment to the supporting tray, which members are adapted to have index or record matter transcribed thereon, or to support separate cards or other devices which bear the index 20 or record matter.

The present invention relates more particularly to index members of relatively large size, which are adapted to present a considerable expanse of record-receiving 25 surface or to support relatively large cards for bearing the recorded matter, or a considerable number of smaller cards presenting in the aggregate a large record-receiving surface.

30 Heretofore, in indices of the type referred to, record-carrying members have been provided comprising, generally, an attaching portion having tongues or other devices for attachment to a support and a record-receiving or card-holding portion secured to one side of the attaching portion, and preferably hinged so that the record-receiving 35 or card-supporting portion may be swung about the attaching portion. The connection 40 between the record-receiving portion and the attaching portion has usually been by means of suitable staples or wires, and the attaching portion extends a distance along the record-receiving portion, thus providing

45 a flap between which and the record-receiving portion the head of an adjacent member may be inserted, whereby the members nest and are maintained in overlapping arrangement. This construction with the 50 parts of the attaching portion and the record-receiving portion superposed and connected by staples, has proved impractical where the devices are of relatively large size, among the reasons for this being that the 55 heads of the devices when inserted between the flaps and the record-receiving portions

of adjacent devices place an undue strain upon the connections between the attaching portions and the record-receiving portions of the devices, and upon the relatively 60 light-weight record-receiving portions of which these devices are usually made, and tend to destroy the connection between the attaching portions and the record-receiving portions. Further, in a device of large size, 65 practical means have not been provided for effectively securing large sized cards on the record-receiving portions. In devices of this kind, it is essential that, while the devices should be removably but firmly held 70 on their support, the record-receiving portions be of relatively light, preferably flexible material, whereby a large number of the devices may be maintained in the index without undue bulk and may be readily 75 swung or otherwise handled.

The objects of the present invention are to provide improvements in index devices of the type referred to, whereby the members may be nested or maintained in overlapping arrangement and readily handled and moved without the liability of injuring the record members; also to provide index devices of this type of relatively 80 great strength and which will adequately 85 support relatively large cards or other devices; also to provide improvements in retaining tabs for devices of this sort; and also to provide improvements in index devices in the other respects hereinafter set 90 forth and claimed.

In the accompanying drawings:

Fig. 1 is a plan view of a portion of an index, illustrating the present invention.

Fig. 2 is a fragmentary plan view of one 95 of the improved record-carrying members.

Fig. 3 is a detail plan view of one of the record-carrying members with portions broken away to show the construction.

Fig. 4 is a section on line 4—4, Fig. 1, on 100 an enlarged scale.

Fig. 5 is a slightly modified form of the record-carrying member.

Fig. 6 is a view of the record-carrying member shown in Fig. 5, with the hinged 105 portion thrown back to show the cards on the rear thereof.

Fig. 7 is a section on line 7—7, Fig. 5.

In the present invention, there is provided a device having an attaching member 110 of relatively heavy material and which is relatively stiff or rigid so that it will

firmly hold the devices in position in the supporting tray or drawer and which is so connected to the record-receiving portion that there is no possibility of the heads of 5 the other devices in nesting destroying the connection between the attaching portion and the record-receiving portion.

In the drawings, A represents a suitable tray or supporting member which is provided with the usual side flanges B beneath which the tongues or other parts of 10 the record device are adapted to engage and whereby the devices are maintained in position in the tray. The improved record devices have attaching portions 10 preferably formed of relatively stiff, heavy material, and record-receiving portions 11 preferably hinged to the attaching portions 10. The record-receiving portions 11 may have the 15 index or record matter directly transcribed thereon or may receive and hold separate cards 12 for the purpose of receiving the record or index matter. The attaching portions 10 are preferably provided with parts 20 13 extending beyond the sides of the record-receiving portion so as to provide the tongues for insertion under the flanges B of the tray. According to the present invention, the attaching portion 10 preferably 25 comprises a single, integral, folded piece of the relatively heavy material, providing in effect, a channel or sheath into which an end of the record-receiving portion may be inserted and secured. The folded material 30 of the attaching portion provides an upper side 14 and a lower side 15, the lower side 15 preferably extending a distance along the record-receiving portion, thus providing a flap so that the head or attaching portion of 35 an adjacent device may be inserted between that flap and the record-receiving portion for nesting the devices. The record-receiving portion 12 and the folded attaching portion 10 are secured together by suitable 40 means, such, for example, as the staples 16 and the upper side 14 of the attaching portion preferably extends a distance below the staple or connecting means 16 so as to brace or reinforce the record-receiving portion. 45 It will be noted from the construction described that when the attaching portion of an adjacent record device is inserted between the flap 15 and the record-receiving portion of one of the devices, such attaching portion 50 will not contact with the staples or other connecting devices, but will wedge into the space between the flap 15 and the record-receiving portion where it is firmly held and any movement toward the staples or connecting devices resisted by the downwardly extending edge of the upper part 14 of the attaching portion. Thus the stresses 55 due to the nesting of these devices are taken upon the relatively heavy and relatively 60 rigid parts of the attaching portion and do

not tend to tear the relatively light weight record-receiving portions from the staples or attaching means. At the same time, the formation of the attaching portion in a sheath or channel form, and the connection 70 of the sides of the sheath or channel by means of the staples, presents a very strong and relatively rigid attaching portion which may be of very considerable length and resists flexing or bending forces to an extent 75 to efficiently maintain the tongues in position under the side flanges of the tray or drawer.

As shown in Figs. 1 and 4, the record-receiving portions may be provided at their lower edges, if desired, with transparent pockets or sheaths 17 which are adapted to receive the lower ends of cards or other members supported on the record-receiving portions. These pockets or sheaths 17, if used, may be connected to the devices in any suitable manner, as by means of staples 18. The record-receiving portion may be provided adjacent its upper end with suitable parts for holding the upper edges of 80 cards or the like, as, for example, the slits 19 shown in Figs. 1 and 2. In addition, it is desirable when these devices are of a relatively large size to provide means for engaging the upper edge of the cards or other members between the ends thereof so as to prevent the upper edge of the card buckling at its center or projecting outwardly and thereby interfering with the other devices 85 in the index. For this purpose the record-receiving portion is provided with a suitable part or tab 20 secured in superimposition on the holder by a securing device which is adapted to contact with the edge of a record member, card, or the like. As illustrated 90 in Figs. 1 to 4, it is preferred to form this tab of an integral part of the record-receiving portion as by cutting or stamping the tab or tongue out of such portion and bending the same downwardly and securing it in 95 downwardly folded position by means of a suitable securing device, as for example, the staple 21. In use, the lower edges of the cards or other record members may be readily inserted in the pockets of the card-receiving portions and the upper edges of the cards sprung to position beneath the tabs 20 and the upper end edges then sprung into 100 positions into the slits 19, whereby the cards will be firmly held in position. The folded over tab 20 may be readily formed and is long lived as the upper edge of the card bears on the securing staple or wire 21 and not on the material of the tab. The securing member or staple also limits the distance 105 the record member or card may be inserted under the tab. There is, therefore, no likelihood that the edge of the record member or card will cut through or sever the tab. The one-piece portion in the form of a channel 110

or sheath provides an unbroken, relatively smooth, upper edge 22, presenting no parts for entanglement with portions of other devices in the index.

head of an adjacent record device, whereby the devices may be nested.

3. In an index or record device, the combination of an attaching portion having parts adapted to releasably connect said device to a support, and a record-receiving portion, said attaching portion comprising an integral channel-shaped piece of relatively heavy material straddling an edge of said record-receiving portion, said record-receiving portion being connected to said attaching portion in its channel, a pocket adjacent the opposite edge of said record-receiving portion for receiving and holding an edge of a card placed thereon, and parts on said record-receiving portion adjacent said attaching portion for holding an opposite edge of said card. 70 75 80

4. In an index or record device, the combination of an attaching portion having parts adapted to releasably connect said device to a support, and a record-receiving portion, said attaching portion comprising an integral channel-shaped piece of relatively heavy material straddling an edge of said record-receiving portion, said record-receiving portion being connected to said attaching portion in its channel, a pocket adjacent the opposite edge of said record-receiving portion for receiving and holding an edge of a card placed thereon, and a tab on said record-receiving portion adjacent said attaching portion for engaging an opposite edge of said card. 85 90 95

5. In an index or record device, the combination of an attaching portion having parts adapted to releasably connect said device to a support, and a record-receiving portion, said attaching portion comprising an integral channel-shaped piece of relatively heavy material straddling an edge of said record-receiving portion, said record-receiving portion being connected to said attaching portion in its channel, a pocket adjacent the opposite edge of said record-receiving portion for receiving and holding an edge of a card placed thereon, and an integral tab projecting from said record-receiving portion adjacent said attaching portion for engaging an opposite edge of 115 said card. 100 105 110 115

6. In an index or record device, the combination of an attaching portion having parts adapted to releasably connect said device to a support, and a record-receiving portion, said attaching portion comprising an integral channel-shaped piece of relatively heavy material straddling an edge of said record-receiving portion, said record-receiving portion being connected to said attaching portion in its channel, a pocket adjacent the opposite edge of said record-receiving portion for receiving and holding an edge of a card secured in superposed position thereon, and a tab on said record-re-

- ceiving portion adjacent said attaching portion.
7. In an index or record device, the combination of an attaching portion having 5 parts adapted to releasably connect said device to a support, and a record-receiving portion, said attaching portion comprising an integral channel-shaped piece of relatively heavy material straddling an edge of 10 said record-receiving portion, said record-receiving portion being connected to said attaching portion in its channel, a part on said record-receiving portion adjacent its edge opposite from said attaching portion 15 for holding an edge of a card thereon, and said record-receiving portion being formed with slits adjacent said attaching portion for holding an opposite edge of the card.
8. In an index or record device, a holder 20 having means for attachment to a support, a holding tab superimposed on said holder whereby an edge of a card to be held is received beneath said tab, and a staple securing said tab in superimposition on said 25 holder and adapted to contact with the edge of the card inserted under said tab, whereby the wear is taken on said staple.
9. In an index or record device, a holder having means for attachment to a support, an integral cut-out tab on said holder bent 30 over to superimposition on said holder, a securing member connecting said tab to said holder and adapted to contact with the edge of a removable record member inserted beneath said tab, whereby the wear is taken 35 on said securing member and the edge of said record member does not wear or cut the material of said tab.
10. In an index or record device, a holder adapted to carry a record member, a tab superimposed on said holder and having a free edge beneath which an edge of a record member may be inserted to releasably retain said record member on the holder, a securing member connecting said tab to the 40 holder and having a part adapted to contact with an edge of said record member to limit the distance said record member may be inserted beneath said tab and preventing said record member edge from cutting 45 or wearing the material of said tab or holder.

JAMES H. RAND, JR.
